UNITED STATES PATENT OFFICE.

EDWARD BOEKENKAMP, OF ST. LOUIS, MISSOURI, ASSIGNOR TO AMERICAN STOVE COMPANY, OF ST. LOUIS, MISSOURI, A CORPORATION OF NEW JERSEY.

MEANS FOR RAISING AND LOWERING COMBUSTION-TUBES.

1,128,937.

Specification of Letters Patent. Patented Feb. 16, 1915.

Application filed November 24, 1913. Serial No. 802,693.

To all whom it may concern:

Be it known that I, EDWARD BOEKENKAMP, a citizen of the United States, residing at St. Louis, in the State of Missouri, have invented certain new and useful Improvements in Means for Raising and Lowering Combustion-Tubes, of which the following is a specification, reference being had therein to the accompanying drawing.

10 My invention relates to improvements in means for raising and lowering combustion tubes.

The object of my invention is to provide means whereby the combustion tubes may be readily raised and supported away from the wick trough so that the burner can be readily lighted and readily lowered after the burner has been lighted. The structure also provides means whereby the combustion tubes may be supported above and away from the wick, so that the oil by capillary attraction will not work its way up on the combustion tubes when the stove is not in operation. In stoves of this character it 25 has been found that when the combustion tubes are left in a downward position, resting in a wick trough, the oil by capillary attraction creeps up on the combustion tubes and causes the stove to smoke when it is 30 first started.

Another object of my invention is to provide a simple, cheap and effective means whereby the combustion tubes can be raised on a burner in which a wick stop is used 35 and having certain details of structure and combination of parts, hereinafter more fully set forth.

Referring now to the drawings: Figure 1 is a vertical sectional view of a burner showing 40 my improved combustion tube raising device and showing the combustion tubes in full line in operative position, and also showing them in dotted lines in a raised position. Fig. 2 is a detached perspective view of the raising lever, showing the same 45 extending through the slot in the guide plate and showing the combustion tube supporting member removed.

Referring now to the drawings, 1 represents the ordinary wick burner having at 50 its upper end the usual trough 2, in which is arranged in the usual manner the wick 3; the said wick being raised and lowered by any desired means, but preferably that

shown in dotted lines Fig. 1. The upper 55 end of the inner wick tube has a diaphragm 4 extending across the central opening therein and provided with a downwardly turned outer edge which is secured to the wick tube by means of solder, as clearly shown in 60 Fig. 1 of the drawings. This diaphragm 4 is provided with an upwardly extending portion 5 having its upper end reduced and screw-threaded as indicated at 6. This central upwardly extending portion 5 of the 65 diaphragm is provided with a central opening 7 therethrough, the purpose of which will be hereinafter more fully described.

Resting upon the flange 8, of the central portion 5 which is formed by the reduced 70 screw-threaded portion 6, is a wick stop 9. This wick stop, as shown, is of a disk-shaped form having perforations therein and having at its outer edge a downwardly and outwardly extending portion 10. The 75 outer end of this downwardly and outwardly extending portion is provided with upwardly and outwardly extending lips 11, which are adapted to extend across the upper edge of the wick 3, to limit the upward movement 80 thereof. These lips are arranged at any desired distance apart and may be of any desired number, as the number of these lips does not in any way affect the operation of 85 the stop.

Screwed upon the reduced threaded portion 6 of the central portion 5 is a nut 12, which is adapted to screw down upon the wick stop 9 and clamp the same tightly 90 upon the ledge 8 carried by the central portion 5. By this structure it will be seen that the wick stop is removable.

The combustion tubes are of the type well-known having the perforated outer wall 13, and inner wall 14 surrounded by a removable chimney 15, supported by the ring 17 carried by the lower end of the outer perforated tube 13. This specific structure of combustion tube and chimney and means for supporting it is described in an application 95 filed October 27th 1913, Serial No. 797,580. The perforated combustion tubes 13 and 14, as shown, rest within flanges on the upper ends of the wick tubes, one on each side of the wick 3, forming the above described 100 trough 2, as is well understood by those skilled in the art. Extending across the space within the central perforated tube 14

is a perforated plate 18, which, as shown, is some distance above the lower end of the tube.

The lower end of the burner 1, is provided on one side with a vertically disposed plate 19, having an obliquely arranged slot 20, the upper end of the slot terminating in a straight horizontal portion 21. Extending through the said slot is an outwardly turned end 22 of the rod 23. The outer end of the outwardly turned portion 22 of the rod on the outside of the plate 19 is provided with a knob for grasping and operating said rod. This rod is provided with a crank-shaped portion 24, below the plate 25, carried by the lower end of the burner 1, and through which the rod 23 passes. The rod from this crank portion 24 extends upwardly through the burner and through the opening 7 in the central portion 5, carried by the perforated plate 4. This rod, as shown in Fig. 1 of the drawing, extends a considerable distance above the threaded portion 6 of the enlarged portion 5. The upper end of the rod is reduced, as indicated at 26 and adapted to fit in a socket 27 carried by the plate 28. This plate 28, as shown, is provided with openings for the purpose of lightening the device and also to allow a free passage of air up through the combustion tubes. This plate 28 rests against the lower face of the transverse perforated plate 18 carried by the interior of the combustion tube and the socket 27 extends through a central opening therein.

When the outwardly turned portion 22 of the vertical rod 23 is in the lower end of the oblique slot 20, the combustion tubes 13 and 14 rest within the flanges on each side of the wick. When it is desired to raise the wick, all that is necessary to do is to move the outwardly turned portion 22 of the rod 23 to the right, which will cause it to travel upwardly on the inclined lower face of the slot and at the same time rotate the rod 23. This causes the rod to travel upwardly and the plate 18 of the combustion tube resting upon the plate 28 will cause the combustion tube to be raised from the flanges. The portion 22 of the rod 23 is moved to the right until it reaches the straight horizontal portion 21, where it will remain with the combustion tubes raised from the flanges so that the burner can be readily lighted. When it is desired to lower the combustion tube, the portion 22 of the rod 23 is moved to the left, which causes the rod 23 to rotate and at the same time to travel downwardly to bring the combustion tubes with 60 in the flanges, as clearly shown in Fig. 1 of the drawings.

The central upwardly extending portion 5 carried by the diaphragm, as heretofore described, is provided with an opening 7 through which the rod 23 passes. This elongated portion 5 serves as a guide for the rod 23 to prevent any twisting, yet allows of the free movement of the rod there-

through.

Having thus described my invention, what I claim and desire to secure by Letters Patent is:

1. The combination with a burner having combustion tubes, of a wick stop, a diaphragm spanning the space within the inner wick tube adjacent the upper end and adapted to support the wick stop, a rod extending upwardly through the burner and through the diaphragm and adapted to support the combustion tubes and means carried by the lower end of the rod for raising and lowering the same, whereby the combustion tubes are raised and lowered from or to the burner.

2. The combination with a burner having combustion tubes, of a wick stop, a plate spanning the space within the inner wick tube adjacent its upper end and adapted to support the wick stop, said plate having an enlarged central upwardly extending portion, a rod extending upwardly through the burner and through the plate and the upwardly extending portion carried thereby, means carried by the upper end of the rod for supporting the combustion tubes, and means operating with the lower end of the rod for raising and lowering the same.

3. The combination with a burner having combustion tubes, of a wick stop, a plate spanning the space within the inner wick tube adjacent its upper end and rigidly supported thereby, said plate having an upwardly extending sleeve at the center thereof and adapted to support the wick stop, a rod extending upwardly through the burner and through the said sleeve, a plate carried by the upper end of the rod and supporting the combustion tubes, and means operating with the lower end of the rod for raising and lowering the same, whereby the combustion tubes are raised and lowered on the burner.

4. The combination with a burner having combustion tubes, of a wick stop, a plate rigidly secured to the inner wick tube adjacent its upper end, a sleeve carried by the said plate and having a screw threaded upper end upon which is adapted to be secured the wick stop, a nut on said screw-threaded portion and a rod extending upwardly through the burner and through the sleeve and adapted to raise and lower the combustion tubes, substantially as shown and described.

5. The combination with a burner having combustion tubes, of a plate extending across the central portion of the burner adjacent its upper end, an upwardly extending sleeve carried by the center of said plate and having a reduced screw-threaded upper

end, a wick-stop surrounding the screw-threaded reduced portion of the sleeve and resting upon the shoulder formed thereby, a nut on said screw-threaded portion, and holding the wick-stop thereon, and a rod extending upwardly through the burner and through the sleeve, and having means at its upper end for supporting the combustion tubes, whereby the raising and lowering of 10 said rod raises and lowers the combustion tubes, substantially as shown and described.

6. The combination with a burner having combustion tubes, of a plate extending across the space within the inner wick tube 15 adjacent its upper end and adapted to support a wick stop, a rod extending upwardly through the burner, a plate removably supported by the upper end of the rod and adapted to support the combustion tubes, a

plate carried by the lower end of the wick 20 tube and having an obliquely arranged slot having its upper end terminating in a horizontal slot, the said rod having an outwardly turned portion terminating in a downwardly turned portion and parallel 25 with the rod, and the lower end of the downwardly turned portion turned outwardly into a horizontal lateral extension passing through the obliquely arranged slot in the plate, substantially as shown and described. 30

In testimony whereof I hereunto affix my signature in the presence of two witnesses.

EDWARD BOEKENKAMP.
